UNITED STATES PATENT OFFICE.

THURE E. DAHL, OF NEW YORK, N. Y.

DESIGN FOR AN ELECTRIC ARM FOR LIGHTING FIXTURES.

61,067.

Specification for Design. Patented June 13, 1922.

Application filed May 31, 1921. Serial No. 473,938. Term of patent 3½ years.

To all whom it may concern:

Be it known that I, THURE E. DAHL, a subject of the King of Sweden, and residing at New York, in the county of New York and State of New York, in the United States of America, have invented a new, original, and ornamental Design for an Electric Arm for Lighting Fixtures, of which the following is a specification, ref-

erence being had to the accompanying drawing, forming part thereof.

The figure is a side view of an electric arm for lighting fixtures, showing my new design.

I claim:

The ornamental design for an electric arm for lighting fixtures, as shown.
